AIR LAUNDER

Richard D. Nichols, Columbus, Ohio, assignor to
The Jeffrey Manufacturing Company, a cor-
poration of Ohio

Application August 15, 1936, Serial No. 96,239

1 Claim. (Cl. 209—494)

This invention relates to an improved air launder or air-table particularly adapted for the dry separation of coal and refuse, though it may be employed for the dry concentration of ores.

An object of the invention is to provide an improved device of the above mentioned class which would be very efficient in operation to obtain the clean separation of coal and refuse which is found in run-of-mine coal.

10 A more specific object of the invention is to provide an air table in which improved means are provided to insure that only refuse enters into the refuse withdrawal pockets thus providing for a clean separation of coal and refuse.

15 Other objects of the invention will appear hereinafter, the novel features and combinations being set forth in the appended claim.

In the accompanying drawings,

Fig. 1 is a plan view of a device comprising my invention;

20 Fig. 2 is a side elevational view of the device of Fig. 1;

Fig. 3 is a transverse sectional view taken on the line 3—3 of Fig. 2 looking in the direction of the arrows;

25 Fig. 4 is a longitudinal sectional view taken on the line 4—4 of Fig. 1 looking in the direction of the arrows;

Fig. 5 is a transverse sectional view taken on the line 5—5 of Fig. 2 looking in the direction of the arrows; and

30 Fig. 6 is an enlarged detailed sectional view taken on the line 6—6 of Fig. 5 looking in the direction of the arrows.

35 Referring to the accompanying drawings, it will be seen that the air-table of my invention comprises a main frame 10 formed by a pair of longitudinally extending I-beams 11, 11 interconnected at the feed end by a rigidly attached motor supporting plate 12 and at the discharge end by a transversely extending member 13. Said main frame 10 is pivotally supported at the feed end from a foundation or column 14 by appropriate pivoted bracket means 15. There are two of said brackets 40 15, one at each side of the main frame 10. Said main frame 10 is preferably maintained in a downwardly sloping position, as seen in Fig. 2, the lower end being adjustably supported upon a jack 16, thus providing for a variable determination of the slope of the air table with a consequent adjustment of the rate of travel of material thereover.

Mounted upon the main frame 10 for oscillating motion with respect thereto is a deck 17, 50 which deck is formed by a pair of longitudinally

extending sideboards 18, 18 to which are rigidly attached longitudinally extending top and bottom angle members 19 and appropriate connecting upright angle members 20. The deck 17 is supported upon the main frame 10 for oscillatory or vibratory motion with respect thereto by a plurality of stub levers 21 having journal bearings at each end carried in bearing blocks 22 and 23 rigidly attached to the deck 17 and the main frame 10, respectively. It may be mentioned that in their normal positions the plane of the stub levers 21 is preferably perpendicular to the plane of the deck 17 and oscillatory motion is equal to each side thereof. If desired, however, the plane of said stub levers 21 may form an acute angle with the plane of the deck 17 thereby to impart a conveying action to any material carried on said deck 17 to aid the travel of material thereacross as influenced by gravity due to the inclination of the table. When this angular relation of the stub levers is employed the air table may be even placed in a horizontal position.

To effect oscillation of the deck 17 with respect to the main frame 10, I provide an oscillating mechanism 24 comprising a crank shaft 25 carrying a fly wheel 26 at one end and a drive pulley 27 at the other end. An electric motor 28 mounted upon plate 12 drives the pulley 27 through a plurality of V-belts 29. Crank shaft 25 is supported upon a bracket 30 and carried by a pair of journal bearings 31, 31. Cooperating with the offset central crank portion of the shaft 25 is a connecting rod or pitman 32 which is pivotally attached to a transverse member of the deck 17 by a bracket 33. It will thus be evident that rotation of the motor 28 will produce oscillatory movement of the deck 17 with respect to the main frame 10.

To aid the return movement of the deck 17 I provide a pair of adjustable coil springs 34, 34 which are attached at one end to an angle member 35 carried by the rear end of the deck 17 and at the other end to the bracket 30.

Referring particularly to Figs. 4 and 5 of the drawings, it is to be noted that the deck 17 also includes a perforated false bottom 36 which is provided with perforations 37 and with which cooperates a plurality of perforated plates 38 provided with perforations 39. Each plate 38 is laterally adjustable by adjusting means 40 and in cooperation with the false bottom 36 provides adjustable valve means for controlling the flow of fluid, such as air, through said false bottom 36 to an individual cell, of which there is a plu- 55

rality beneath the hereinafter described screen plate 48, as seen in Fig. 4 of the drawings.

It may be mentioned that the deck 17 is formed into a plurality of sections 41, 42 and 43 which are substantially duplicated except for differences hereinafter described. Each of said sections 41, 42 and 43 will be provided with one or more individually controllable perforated plates 38.

Positioned below each of the deck sections 41, 42 and 43 is an air chamber or air conduit 44 which provides an air-tight communication therewith by a flexible encircling skirt 45.

Carried between the sideboards 18 of the deck 17 and formed as an independently removable unit which may be bodily lifted from said deck 17 and replaced by a different unit, is a screen section 46 formed by a pair of longitudinally extending sideboards 47, 47 adapted to ride upon the false bottom 36 and carrying intermediate their tops and bottoms, a perforated screen plate 48. The screen section 46 is clamped in the deck 17 by a plurality of transversely extending angle members 49 which are removably attached to the angle members 19 of deck 17 as by nuts and bolts 50. This removable structure is provided so that the screen plate 48 may be readily renewed by keeping on hand a number of screen sections 46 having screen plates 48 with different sized perforations, thus providing for the treatment of coal of different size ranges. It will, of course, be evident that the size range of the coal being treated will determine to a large extent the amount of perforated opening which should be present in any screen plate 48.

Referring particularly to Figs. 3, 4 and 6 of the drawings, it is to be noted that each of the deck sections 41, 42 and 43 is provided with a transversely extending refuse discharge chute 51 formed by a pair of spaced transversely extending plates or boards 52, the tops of which are attached to plate 48 and the bottoms of which ride upon the false bottom 36. The false bottom 36 is provided with a transversely extending discharge chute 53, in alignment with the opening 51, which leads to a chute 54. Chute 54 is mounted upon a pair of inverted U-shaped side brackets 55, 55 (see Fig. 3) which are supported upon side brackets 56, 56 carried by the I-beams 11, 11. The cooperating brackets 55 and 56 support the chute 54 for oscillatory movement which is required due to the vibratory movement between the deck 17 and the main frame 10.

To insure a relatively tight connection between the chute 54 and the false bottom 36 of the deck 17 I provide a pair of transversely extending channel members 57, 57 (see Fig. 4) adjacent the top edges of the chute 54 which carry a pair of elastic members 58, 58 which cooperate with a second pair of channel members 59, 59 carried by the false bottom 36.

The deck 17 also carries adjacent each refuse draw, a pair of transversely extending angle members 60, 60 which are rigidly attached to the side boards 18, 18, and which carry appropriate reinforced Z-shaped plates 61, 61 which cooperate with the channel members 59 to hold them in proper position and which also cooperate to provide an air chamber below the perforated false bottom 36.

As best seen in Fig. 3 of the drawings, within the chute 54 are a plurality of upright partitions 62 and 63, the latter only extending part-way up from the bottom. To the lower ends of said partitions 62 and 63 is connected an abutment rod 64 which extends longitudinally of the chute

54. It will be understood that material moving downwardly through the chute 54 will be discharged to either side of the abutment rod 64. Below the bottom of the chute 54 is a semi-circular trough 65 which receives material discharged through the chute 54 and becomes filled thereby. The trough 65 cooperates with the push rod 64 and the chute 54 to effect the discharge of material from the chute 51 of the deck 17 at a controllable rate. This rate is effected by controlling the speed and angle of oscillation of the trough 65, which trough 65 is continuously oscillated when the deck is in motion.

To effect the oscillatory motion of the trough 65 I mount said trough on stub shafts 66 and 67 (see Fig. 3) which are carried in appropriate journals in brackets 56. Stub shaft 67 has rigidly connected thereto a crank lever 68 having a bifurcated end adapted to receive a transversely extending oscillating shaft 69. As seen in Figs. 10 and 2 of the drawings the shaft 69 may be oscillated from a crank 70 driven from crank shaft 25 by appropriate chain and sprocket mechanism 71 and each of the three refuse discharge mechanisms associated with the deck sections 41, 42 and 43 will be operated from said shaft 69.

Cooperating with each of the crank levers 68 is a pair of adjustable stops 72 which provide for the individual adjustment of the angular motion of each of the troughs 65 during operation.

Surrounding each trough 65 is a receiving hopper 65' which extends transversely of the main frame 10 and is rigidly supported thereby. Hopper 65' will receive the material which is discharged by the trough 65 and direct it to a transversely extending screw conveyor mechanism 73 by which said refuse will be discharged laterally from the table through a discharge spout 74. All of the screw conveyor mechanisms 73 will be operated from the motor 28 through appropriate drive chain and sprocket mechanism 75 (Fig. 1) driven from a shaft 76, which in turn, is driven by the chain and sprocket mechanism 71.

It will be evident that any material which is received in the chute 51 will flow into the trough 65. As said trough 65 oscillates the push rod 64 will be effective to push the material over the lateral edges thereof in amounts determined by the angle of oscillation thereof and its rate of oscillation. This material which is pushed over the sides of the trough 65 will be guided by the hopper 65' into the screw conveyor mechanism 73 by which it will be discharged. It is to be particularly noted, as will be hereinafter described in more detail, that the refuse discharge mechanism, including particularly the trough 65, should be adjusted to maintain the chutes 51 and 54 full of refuse at all times. This is very important in effecting a satisfactory separation of materials, for it insures the presence of a refuse bed on the screen plate 48 at all times and prevents the entrance of coal into the refuse discharge chute 51, as will be hereinafter described in more detail.

It is to be noted that the entire screen plate 48 of all the sections 41, 42 and 43 lies in a single plane. It has been found from exhaustive experimentation that this type of deck may be employed particularly in connection with the refuse control means now to be described, to effect a very efficient separation of coal and refuse.

As best seen in Figs. 4 and 6 of the drawings, the refuse discharge chute 51 provides a trans-

versely extending opening which extends completely across the deck 17 between the side boards 41, 41. Cooperating with the opening to each of the chutes 51 is a cover or hood 80 formed by a transversely extending top plate 81 having at each end an upwardly extending plate 82 provided with a pair of elongated arcuate openings 83, 83 with which cooperate clamping screws 84, 84. The plate 81 is hingedly attached to the 10 screen plate 48 adjacent the lower or downstream edge of the opening to chute 51, by a plurality of hinges 85.

Adjacent the forward or upstream edge of the plate 81 I provide a normally vertical plate 86 which is pivotally attached to said plate 81, as by a continuous hinge 87. To provide for adjustment of the plate 86 with respect to the plate 81, a threaded bolt 88, of which there are a plurality, threads into a pivoted nut 89 carried upon a downwardly extending bracket 90, supported by plate 81, which bolt 88 extends through the plate 86 and is provided with a nut 91. The nut 91 is keyed to the bolt 88 to permit ready turning of said bolt 88 with respect to the plate 86. Thus by applying a tool to the nut 91, the bolt 88 may be rotated in either direction to swing the plate 86 with respect to the plate 81 about the hinge 87. It is also evident that the plate 81 may be swung about the hinge 85 and held in adjusted position by the screws 84. It is to be noted that the plate 86 is positioned directly above one of the boards 52 forming the chute 51, and thus the air moving upwardly through the perforated plate 48 is not caught under the hood 80.

It is also to be noted that the plate 86 has its bottom edge spaced above the screen plate 48 thereby to provide a longitudinally extending port 92 which provides the sole entrance from the deck to the refuse discharge chute 51. It may be mentioned that the plate 86 has such a height that the port 92 is always fed only with stratified refuse. That is, in the operation of the device, the instantaneous variations in the depth of the refuse bed will be such that the top of the refuse bed is always above the bottom of the plate 86 and always below the top thereof. Thus, instantaneous variations in the depth of the refuse bed will not result in a discharge of refuse into the succeeding compartment or a discharge of coal into the refuse chute 51.

In the operation of the device comprising my invention, air under pressure will be supplied to the air chambers or conduits 44 and thence through the screen plate 48 as controlled by the individual valves 38. Oscillatory motion will be imparted to the deck 17 by the oscillating mechanism 24. At the same time the refuse withdrawal mechanism, including the oscillating troughs 65, will be operated, and the spiral conveyor mechanism 73 will be operated to remove accumulated refuse.

Coal will be fed to the deck at the upper end thereof over a feed chute 95 and will spread out over the screen plate 48. The combined actions of the upward currents and vibratory motion will

be effective to stratify the fed materials, such as run-of-mine coal, with the refuse, such as shale, pyrite and bony coal, in the bottom strata, and the clean coal on top. The lowermost strata of the stratified bed will be directed to the refuse discharge chute 51 by the hood mechanism 80, which hood mechanism 80 will be effective to insure that only refuse enters said chute 51. This selective action of the hood 80 is possible by virtue of the fact that the chute 51 will be maintained continuously full of refuse by so adjusting the oscillation of refuse discharge trough 65 that there is always a refuse bed on the screen plate 48 which has a depth at least equal to the height of port 92, but not greater than the height of plate 86. As a consequence, refuse will be discharged at the rate it forms, after the deck is once adjusted in operation, and the baffle plate 86 will be operative to compensate for instantaneous variations in the depth of the refuse bed, insuring that no refuse be discharged over the top of plate 81, at the same time insuring that no coal will enter the port 92.

It will, of course, be evident that the heaviest gravity material will constitute the refuse in the draw station associated with the first deck section 41, and the lighter gravity refuse will be passed over as a clean product into the following sections. By employing three successive deck sections 41, 42 and 43, I am able to remove the refuse strata consecutively in accordance with decreasing specific gravities.

The final product which is discharged over the lower end of the screen plate 48 will be clean coal substantially free from any refuse.

It is to be particularly noted that both the hood 80 and the refuse control mechanism, including particularly the trough 65, are important features which contribute to the improved results which I realize. That is, unless the chute 51 is maintained full of refuse it is very difficult to insure that the stratified refuse on the screen plate 48 will always be above the top of the port 92, and without the hood mechanism 80 it is practically impossible to prevent some coal from falling into the refuse discharge chute 51.

Obviously those skilled in the art may make various changes in the details and arrangement of parts without departing from the spirit and scope of the invention as defined by the claim hereto appended, and I therefore wish not to be restricted to the precise construction herein disclosed.

Having thus described and shown an embodiment of my invention, what I desire to secure by Letters Patent of the United States is:

A separator deck comprising a perforate plate, an upright discharge chute leading from said plate, a cover for said chute constructed and arranged to cover the vertical projection thereof, said cover including a pivoted top plate and a baffle plate pivoted to said top plate and positioned above said perforate plate.

RICHARD D. NICHOLS.
